The ornamental design for a base for a bathing enclosure unit, as shown and described.

DESCRIPTION

FIG. 1 is a perspective view taken from the top and front of a base for a bathing enclosure showing our new design;

FIG. 2 is a left side elevational view thereof, the right side being a mirror image of the left side;

FIG. 3 is a top plan view thereof;

FIG. 4 is a cross-sectional view thereof taken on line 4—4 of FIG. 3; and,

FIG. 5 is a cross-sectional view thereof taken on line 5—5 of FIG. 3.

The broken line representation of openings and the fragmentary broken line representation of bathroom walls in FIG. 1 are for the purpose of illustration only and form no part of the claimed design.
